COMBINED JEWEL BOX, CLOCK, AND RADIO

Karl Luft, St. Louis, Mo.

Application October 31, 1955, Serial No. 38,643

Term of patent 14 years

(Cl. D86—9)

FIG. 1.

FIG. 2.

FIG. 3.

FIG. 4.

FIG. 5.

Fig. 1 is a top plan view of a combined jewel box, clock and radio, showing my new design;

Fig. 2 is a front elevational view;

Fig. 3 is an end view;

Fig. 4 is a rear elevational view; and

Fig. 5 is a perspective view of the combined jewel box, clock and radio with the lid in a raised position.

I claim:

The ornamental design for a combined jewel box, clock and radio, substantially as shown and described.
